UNITED STATES PATENT OFFICE.

RAMON J. LOZON, OF CHICAGO, ILLINOIS, ASSIGNOR TO KING LOCK COMPANY, OF
CHICAGO, ILLINOIS, A CORPORATION OF ILLINOIS.

LOCK.

1,419,393.

Specification of Letters Patent. Patented June 13, 1922.

Application filed February 11, 1920. Serial No. 357,766.

To all whom it may concern:

Be it known that I, RAMON J. LOZON, a citizen of the United States, residing at Chicago, in the county of Cook and State of Illinois, have invented certain new and useful Improvements in Locks, of which the following is a description.

My invention relates to that general class of devices known as locks, and more particularly that type known as plate tumbler locks. The invention has among its objects the production of a device of the kind described that is simple, convenient, durable, compact, efficient, attractive and satisfactory for use wherever found applicable. The invention has among its further objects the production of a lock which cannot be easily picked or operated without its key, and also a lock which may be economically manufactured and assembled. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Fig. 1 is a front elevation of the lock;

Fig. 2 is a rear elevation of the same;

Fig. 3 is a sectional view through the casing, the plug and tumbler shown in elevation;

Fig. 4 is a sectional view and side elevation taken substantially on line 4-4 of Fig. 3;

Fig. 5 is a sectional view taken substantially on line 5-5 of Fig. 3;

Fig. 6 is a sectional view taken substantially on line 6-6 of Fig. 3;

Fig. 7 is a sectional view taken substantially on line 7-7 of Fig. 4;

Fig. 8 is a sectional view taken substantially on line 8-8 of Fig. 3;

Fig. 9 is a sectional view taken substantially on line 9-9 of Fig. 3;

Fig. 10 is a sectional view similar to Fig. 5, showing the key withdrawn;

Fig. 11 is a view in elevation of one of the tumblers;

Fig. 12 is a similar view of another tumbler; and

Fig. 13 is a section view similar to Fig. 8 showing a modified construction.

Referring to the drawings, 1 represents a casing of the desired size, shape or design and material, and constructed in any suitable manner, within which is arranged a plug 2, which is preferably made in a plurality of sections, as shown two, secured together by a collar 3 or equivalent means for the purpose. The plug is preferably milled or otherwise formed with a key-way for the key shank 4. Any suitable means may be provided for operatively connecting the plug with a lock bar or bolt or the equivalent, it being immaterial as to whether the connecting means is at the front or rear end of the plug or an intermediate point. In the construction shown, I have secured a plate 5 arranged at the rear end of the plug, and provided with a lug 6 arranged to cooperate with a locking bar or bolt 7, it being understood that the particular mechanism operated or controlled by the plug, or where installed, is immaterial in so far as the present invention is concerned. In the particular case illustrated, the plate 5 is secured to the plug and maintains the parts 2-2 together at the inner end.

The casing 1 is preferably formed with grooves 11 and 12 on opposite sides of the same at the interior. Carried in the plug or barrel 2 are the desired number of tumblers, which are of lengths to be confined within the plug but movable lengthwise in the plug so as to engage with one or the other of the slots 11 and 12, as shown, when the key is withdrawn. The tumblers, as most clearly shown in Fig. 8, are of lengths to be confined entirely within the plug when the key is inserted, and I have shown a plurality of series of tumblers 14, 15 and 16. As shown, the plug is milled or otherwise cut away to form the slots or openings 17, 18 and 19, the tumblers being of a width to closely fit the slots at the sides. I have shown the series separated by projecting parts 20. The advantage of making a plurality of series of tumblers with one or more in a series, is that the same may be modified so that the lock may not be easily picked. I have shown a number of plate tumblers 14 and several tumblers 15, which may be made of thin

sheet steel and stamped out or manufactured in any suitable manner. The tumbler 16, however, I prefer to make somewhat heavier, and there is provided means for positively actuating this tumbler when the key is withdrawn so as to positively move the same in engagement with the casing. Each of the tumblers is provided with an opening or perforation 21 of a size to closely fit the edges of the key, but ordinarily with a clearance on each side. The key in the construction shown is preferably formed with the grooves and ridges 23 and 24, so as to fit the irregular shaped key-way. It will be noted by referring to Fig. 6 that the tumblers 15 are provided with a somewhat longer opening or perforation than the tumblers 14 and 16, the key being slightly wider at this point, as indicated at 22.

As before mentioned, I prefer to provide means for positively controlling a portion of the tumblers, as shown, tumbler 16. For this purpose I provide a spring 27 or the equivalent. In the construction shown, I cut away a portion of the plug at one side, as indicated at 25-26, and insert a spring 27, which is preferably coiled with one end engaging in the opening 28 and the other end extended into the opening 25 and through an opening 29 in the tumbler. This being the rear tumbler, it is extremely difficult to manipulate the same except with the proper key. I have shown the tumblers 14 and 15 cut away at the sides (see Fig. 12), as indicated at 30, so as to clear the spring or member 27 and drop by gravity when the key is withdrawn. Obviously, however, it may be so arranged that any one or more of the tumblers in addition to the tumbler 16 may be controlled similar to tumbler 16.

With some types of locks it has been possible to manipulate the tumblers with a suitable tool or instrument other than the key, particularly if a turning pressure was at the same time applied to the plug, tending to turn the same so that the tumblers would bind and not slip back into engaging operative positions, and might gradually be forced into the plug. With my preferred form of lock, movement of the tumblers to their position within the plug is prevented, except when the proper key is inserted and no turning pressure applied to the key until the tumblers have been completely retracted or retrieved to their inoperative position. Any suitable means may be provided for locking the movement of the tumblers against retraction upon a turning movement of the plug simultaneously with the aligning of the tumblers. As shown, I cut a portion of the casing at the grooves 11 and 12 as indicated at 32, so that there is a projecting part 33 at each side, the same being spaced from each other a distance equal to the width 65 of the tumbler. The same is preferably cut

back as indicated at 36, so that a substantially sharp edge 34 is formed. As shown, the tumblers are cut back as indicated at 35 so as to form a sharp point or engaging prong which will cooperate with the edges 34 under certain conditions, as hereinafter described. The tumblers have a portion of the edges, as at 37, of sufficient length to afford a bearing in the plug and casing.

The operation of the lock when a key is inserted is obvious. Before the insertion of the key the tumblers are substantially in the positions shown in Fig. 10 or in equivalent positions, so that the same are engaging with the casing in one or the other of the grooves 11 or 12. Upon inserting the key (see Fig. 6), the key shifts the tumblers back and forth so as to align them at the ends when the key is fully inserted. The key may then be turned, and through the plate 5 and lug 6 or their equivalent, shift the bolt 7. If an unauthorized person without a key endeavors to manipulate or pick the lock, he may use an unauthorized key, but ordinarily it is difficult, if not impossible, to produce a duplicate key without having the authorized key for a pattern. Generally in tampering with locks, the person picking the same inserts a tool of suitable size and shape into the key-way and manipulates the tumblers regardless of whether the same are pin or plate tumblers, so that the same are aligned, releasing the plug and permitting its turning. In so manipulating the tumblers with a tool, the prowler may slightly turn the barrel regardless of the type of lock, whether plate or pin tumblers, so that when he works his tool to actuate the tumblers, the friction or pinching of the tumbler at the puncture of the barrel and casing will have a tendency to temporarily retain the tumblers until he has succeeded in aligning them, after which the plug may be turned. With the present lock, it is necessary to manipulate a portion of the tumblers in one direction and a portion in the other, making it somewhat difficult to secure an alignment, but if pressure is applied by turning the plug so as to bind the tumblers and retain them until all have been aligned, applying such pressure will cause the tumblers to be positively locked against a retrieving movement. As most clearly shown in Fig. 9 in the dotted lines, if there is any slight turning or application of pressure to turn the plug when the tumbler is in its operative locking position, as indicated by the dotted lines, upon attempting to move the tumbler lengthwise into the plug, the face 35 will engage with the point 34, thereby positively preventing movement of the tumblers while the pressure is so applied. If pressure is not applied, owing to the number of gravity operated tumblers as well as the spring controlled tumbler 16, of which there

may be any number, it is necessary to manipulate the tumblers in opposite directions and for varying distances. Likewise, tumblers 15 have to be controlled and these have 5 a larger opening than the tumblers 14 or 16. The result is that the lock is practically non-pickable, even by an expert. This has been found true even when a sample lock was employed and the same partially cut away so 10 as to enable the tester to pick the same, if possible, by giving him a complete view of the position of the parts.

In the construction shown in Fig. 13, an equivalent construction consists in a casing 15 38 arranged to receive the plug 39 carrying the tumblers 40. With this particular construction the casing is formed with recesses 41 and the tumblers with prongs 42. With this type, while the tumbler may be easily retrieved or retracted by the proper key, if it is attempted to retrieve the same with a picking tool, or by picking and applying pressure to the plug, the prongs 42 will engage in one or the other of the recesses 41, 20 thereby locking the tumblers against movement.

I have not considered it necessary to describe all of the possible uses of the particular lock mechanism shown and described or 30 complete locks, as lock units of this type are well known, and the application of the same may be made wherever the lock is desired. The lock is particularly desirable, however, for use on automobiles, lockers, 35 cabinets, desks, padlocks and the like, where a safe and non-pickable lock is desired.

Having thus described my invention, it is obvious that various immaterial modifications may be made in the same without departing from the spirit of my invention; 40 hence I do not wish to be understood as

limiting myself to the exact form, construction, arrangement and combination of parts herein shown and described or uses mentioned.

45

What I claim as new and desire to secure by Letters Patent is:

In a key-controlled lock, the combination of a suitable casing, a cylindrical barrel rotatably arranged therein, a plurality of 50 tumbler plates carried by and transversely movable through said barrel into engagement with the casing upon the withdrawal of the key, whereby the barrel will be locked against rotation, said tumbler plates being 55 provided with keyways therethrough of varied sizes, and interengaging means between the casing and the plates whereby the plates will be locked against movement upon a simultaneous lengthwise movement of the 60 plates and rotation of the barrel, comprising arcuate, circumferentially extending shoulders on the plates and co-operating overhanging, arcuate lugs on the casing for positively engaging the plates at said shoulders, and spring means for moving a portion of said tumbler plates into operative engagement with the casing independently 65 of the key, the others of said tumbler plates being gravity controlled, whereby the withdrawal of the key will move the tumbler plates comprising said portion in a direction opposite to that of the casing engaging movement of the remaining tumbler plates.

In testimony whereof, I have hereunto 70 signed my name in the presence of two subscribing witnesses.

RAMON J. LOZON.
